Primary Examiner—Freda Nunn[57] **CLAIM**

The ornamental design for a hand held terminal, as shown and described.

DESCRIPTION

FIG. 1 is a front perspective view of a hand held terminal; FIG. 2 is a front view thereof; FIG. 3 is a right-side elevation view thereof; FIG. 4 is a back view thereof; FIG. 5 is a top view thereof; and, FIG. 6 is a bottom view thereof.

The keys are shown in broken lines in FIGS. 1 and 2 for illustrative purposes only and form no part of the claimed design.
